ELECTRIC MAKE-AND-BREAK DEVICE

Robert Tucker, Rocky River, Ohio

Application April 19, 1947, Serial No. 742,570

1 Claim. (Cl. 171—97)

1

This invention relates to the art of electric circuit making and breaking devices which are especially well adapted for use in connection with electrically charged fences for stock.

There have been various devices for the purpose above indicated but in some instances the interruptor must necessarily be combined inseparably with the transformer; in some if not all instances the interruptor must always occupy upright position; while in all prior instances, so far as I am aware, the devices are of a comparatively complicated and expensive nature and hence rather prohibitive.

It is therefore one object of my present invention to provide such an interruptor which may be depended upon to function in its normal manner and also in an efficient manner while occupying any position.

Another object is to provide such an interruptor which may be used as a unit separate from the transformer or may be combined with the transformer.

A further object is to design such an interruptor which may be readily installed by the user without any particular trouble or knowledge or skill and in which any part, as for instance the battery, may be renewed at any time necessary and with the same degree of convenience and economy.

Other objects will appear from the following description and claims when considered together with the accompanying drawing.

Fig. 1 is a diagrammatic view of one form of device;

Fig. 2 is a sectional view of a part thereof, on line 2—2 Fig. 3;

Fig. 3 is a view taken on line 3—3 of Fig. 2;

Fig. 4 is a diagrammatic view of another form of my device; and

Fig. 5 is a sectional view of a part thereof.

According to my first form of device, as illustrated in Figs. 1 and 2, there may be employed an inexpensive small size of battery 1 which is included in the electric circuit with the manually-operated switch 2 for closing and opening the same as may be desired. Within this circuit there is included also the unitary piece of equipment which may be here identified as an electric interruptor 3 and which is illustrated in its detailed construction in Figs. 2 and 3. This piece of equipment 3 has an electric terminal 4 connected in circuit with the battery 1 and switch 2 and with one side of the electric contact means 5, the other side of the contact means 5 having electric connection in this same circuit with the

2

field coil 6 which, in turn, has electric connection with the other electric terminal 7. The parts of this unitary interruptor 3 are mounted within the housing 8 of suitable electric insulation material, which may be anchored in position by means of the bolt holes in the base thereof, these holes in the flanged base being indicated by reference numeral 9.

The unitary interruptor 3 is adapted and intended to be connected electrically to the primary circuit P of an electric transformer, this primary being arranged also in circuit with the battery 1, as indicated in the drawing. The secondary coil S of the transformer is grounded and is also connected to the stock fence which is to be charged. It is to be understood, of course, that the critter in the field will complete the circuit through the ground as it comes into contact with the wire of the fence, this being the usual arrangement in such devices.

Reverting now to the unitary interruptor 3, I will explain other details thereof. The two companion members of the electric contact means 5 are normally forced into disengaged position by means of the spring arm 5a upon which one of the contact members is mounted and with which the cam 10 is adapted to have operative engagement for closing the contact 5. The cam 10 is rotatably mounted upon the post 11 arranged axially within the housing 8 of the interruptor 3. A coil spring 10a engages about the hub of the cam 10 and has its other end anchored in the wall of the housing 8, the normal tendency of this spring being to turn the cam 10 in a clock-wise direction, as viewed in Fig. 3 of the drawing, so as to effect closing of the contact. The armature 12 is mounted upon the hub of the cam 10 and is adapted to effect a rotatable movement of the cam 10 in accordance with the energization and de-energization of the armature. When the circuit including the field coil 6 is closed in the regular operation of the device, the armature 12 will be caused to turn counter-clockwise, as viewed in Fig. 3 hereof, so as to register with its pole piece 12a and thereby permit the spring arm 5a to effect opening of the contact 5 upon moving the cam 10 out of engagement therewith. Whether the cam 10 is actually moved entirely out of engagement with the arm 5a, it is moved sufficiently in the direction indicated to permit opening of the contact 5 for the purpose stated. Such opening of contact 5 will break at once the electric circuit so as to de-energize the field coil 6 and release the rotatable armature 12 to the influence of the coil spring 10a.

which returns the cam 10 and the armature 12 to the position in which cam 10 closes the contact 5, whereupon the same operation may repeat itself.

The armature 12 is provided with a stop pin 13 which is adapted to engage the block of the terminal 4, although the inertia of the rotatable parts may be so nearly balanced with respect to the force of the spring as to render such a stop means practically unnecessary for limiting the return movement of the armature 12. This stop means will serve to determine and maintain the initial position of the armature before the device is set into operation.

It is to be understood that, as long as the circuit is closed by the hand switch 2, the interruptor 3 will continue to operate in the manner above stated, so as to effect a make-and-break of the current through the circuit. That is, assuming that the armature 12 is at rest, as indicated in Fig. 3 hereof, the cam 10 holds the contact 5 in closed position. Under such conditions, the circuit is completely closed through the field coil 5 and the magnetic impulse thereof causes the armature 12 to rotate counter-clockwise against the impulse of the spring 10a. Such rotation of the armature 12 is accompanied also by like rotative movement of the cam 10, with the result that the contact 5 is opened and the circuit is thereby broken. Thereupon, the armature 12 and cam 10 are released to the influence of the spring 10a which returns the parts to the position indicated in Fig. 3 hereof. The torsion spring 10a is of such tension that it will allow proper time interval to elapse during the rotative movement of the armature 12 in counter-clockwise direction; and, likewise, the same relation between the weight of the armature 12 and the tension of the spring 10a will determine the time interval required for the return of the armature 12 to its original position indicated in Fig. 3 hereof.

In the first form of device, as above described and indicated in Figs. 1 and 2 hereof, the field coil 6 is entirely separate from the transformer, the unit 3 being connected to the primary P of the transformer in the usual manner. I will now refer to another form of my invention in which the field coil may serve also as the primary of the transformer, as illustrated in Figs. 4 and 5 hereof. In this modified form of device, the unitary interrupter 3' includes also the transformer within the same housing 8'; but, as above explained, the field coil serves also as the primary winding of the transformer. As a result of this modified arrangement, the field coil and the transformer windings together comprise only two coils instead of the three coils required in the first arrangement above described. In this second form of device, the several parts thereof are indicated by reference characters corresponding to those employed to indicate the corresponding parts in the first form of device. For instance, whereas the electric contact is indicated by reference numeral 5 in the first form of device, it is indicated by reference numeral 5' in the second

form of device. Whereas the primary coil of the transformer is indicated by reference letter P in the first form of device, reference character P6 in the second form of device indicates the coil which serves both as the field coil and the primary coil of the transformer; and the secondary of the transformer, in the second form of device, is indicated by reference letter S'.

One important and practical feature of my present invention is its comparative simplicity and its correspondingly low cost. The unitary form of interruptor may be easily handled and installed and it is not necessary for it to assume upright position in order for it to operate in the manner intended. This is true of both forms of my present invention, regardless of whether the interruptor is entirely separate from the transformer as in the first form of device, or is merged therewith as in the second form of device. The unitary interruptor, in either form of device, may be located at any point desired; and the entire system which embodies my present invention as part thereof, may be operated in a dependable and efficient manner without any particular attention being required in either the installation or the upkeep thereof.

What I claim is:

An electric circuit making and breaking device comprising a single annular form of electric coil serving to provide a magnetic field and serving also as the primary coil of an electric transformer, an electric switch in circuit with said coil for controlling the current therethrough, spring means tending normally to close said switch, an armature rotatably and concentrically mounted in operative relation to said coil and having rotatably-actuated means for opening said switch against said spring, said parts being so constructed and arranged that the energization of said coil will actuate said armature in a rotatable manner so as to thereby effect temporary opening of said switch and the de-energization of said coil, and an electric coil concentrically arranged with respect to the aforesaid annular form of coil so as to constitute therewith the secondary coil of an electric transformer, and a housing enclosing all of said parts so as to thereby constitute a unitary and compact form of device.
